UNITED STATES PATENT OFFICE

HARRY V. MARSH, OF CHICAGO, ILLINOIS

DISPLAY RACK

Application filed November 8, 1930. Serial No. 494,216.

The present invention relates to display racks for retail advertising and sale of merchandise and has particularly to do with an inexpensive display rack which is made of sheet material and which may be set equally well upon floor or counter.

The object of the invention is to provide a stand which will present not only adequate advertising space and a sample box of the article in prominent position thereon, but in addition thereto will provide shelves or space to carry a small supply of the article on display for immediate sale. The device is particularly designed so that a retailer will be relieved of all burden of finding shelf space for a new commodity and because of the attractiveness of the display, such retailer may readily be induced to display for a sale a commodity for which no public demand has been created.

Additionally, it is the object of the invention to supply a stand or rack of the character described having additional storage space to carry a small stock of merchandise concealed from view. Another object of the invention is to provide a new and improved display stand which may be constructed of inexpensive materials and which requires little labor and time to erect.

These, and such other objects as may hereinafter appear, are attained by the novel construction, unique combination and improved arrangement of the parts of the invention, one form of which is hereinafter described.

One sheet of drawing illustrative of such single form of the invention is hereto attached and made a part of this specification. In the drawing:

Figure 1 is a perspective view of the device, partly assembled;

Figure 2 is a plan view of a blank forming a part of the front and the sides of the device;

Figure 3 is a plan view of a blank of a section which forms the upper section of the front of the device;

Figure 4 is a plan view of a blank providing a shelf in the device and also reinforcing its structure; and

Figure 5 is a plan view of a blank used as a spacer element.

Like reference characters are used to designate similar parts in the drawing and in the description which follows.

As illustrated, the device may comprise four blanks, although this number may be reduced to three by joining the blanks shown in Figures 2 and 3 into one blank.

The first blank is of sheet material and is illustrated in Figure 2. It may be folded to form the frame or supporting structure of the device; the second blank, illustrated in Figure 2, may be of similar material and is slit and articulated to form an inset joined to the blank illustrated in Figure 2; the third blank illustrated in Figure 4 spans the lower section of the device to reinforce it and provide a shelf; and the fourth part is a blank which is horizontally disposed in the rear of the device to assure lateral strength.

The principal blank 9 comprises wings 10 and 12 separated from the front 11 by scores 40 and 41. In assembly, wings 10 and 12 are at right angles to the front 11, and are complementary, opposed and parallel.

Intermediate the wings 10 and 12, when assembled into a U-shaped frame, there is seated a horizontally disposed sheet 43 (see Figure 4) having a flap 44 articulated downwardly on the line of score 57 and a second flap 45 articulated upwardly on score 56. The shelf 43 is secured in the side walls 10 and 12 by hook-ears 37 and 38, on flaps 45 and 44, respectively, and pointed in the same direction, said ears being insertable into slots 29 and 30 in said side walls 10 and 12. Thus a shelf with an external drooping flange and an upwardly turned internal flange is provided, the shelf providing a concealed storage space for merchandise.

Depending from the front 11 is an extension 13 which is adapted to be articulated rearwardly on a score 47 to form a merchandise shelf. An extension 14 is articulated from extension 13 on a score 48, said extension in the assembled device being vertical and forming a back for shelf 13. There are hook ears 32 upon the upper corners of back or extension 14 which are seated in the slots 100

28 in side members 10 and 12. A further extension 15 depending from extension 14 is separated therefrom by score 49 and provides a second merchandise display shelf. A 5 short extension 16 is separated from section 15 by a score 50. Said extension being turned downwardly from shelf 15 and having hook-ears 33 adapted to be inserted into the rectangular apertures 27 in members 10 and 12 10 to be locked therein.

On blank 8 (Figure 3) which is generally rectangular, and at its lower corners are hook-ears 36 which are also adapted to be seated in rectangular slots 27 so as to lock 15 therein in parallelism with hook-ears 33. The lower section of blank 8 is designated 24, and it is separated from two opposite aligned smaller sections 21 by scores 51. Intermediate said sections 21 is an extension 24a. 20 From extension 24a an extension 23 depends, there being an intermediate score 52. From section 23, a further extension 18 depends, there being a score 53 therebetween. Section 18 terminates at its top in a T-shaped 25 locking end or tongue 64. Continuous parallel slits define the edges of sections 24a, 23, and 18, the top of section 18 and tongue 64 being formed by other slits extending from the upper end of such parallel slits.

30 From sections 21, there are extensions 19, having at their sides hook-ears 35, and from said extensions 19 there is a larger extension 20 separated from section 18 by the slits from the top thereof and the tongue 64. Between 35 sections 21 and sections 19 are scores 54, and between sections 19 and section 20 are scores 55.

On the sides of section 20 are hook-ears 34, and adjacent its lower edge is a T-shaped slot 40 31 into which tongue 64 may be inserted when sections 19 are laid against sections 21 by articulating the blank on scores 54 and 55. Upon such assembly, extension 24a remains 45 upright, while section 23 becomes a shelf for a single package of merchandise. Said shelf 23 has a back 18 locked into proper position by engagement of tongue 64 in slot 31. Sections 21 and sections 18, while both obliquely disposed, lie in different planes.

50 The blank 71 (Figure 5) having slots 39 at its end is locked in slots 26 in the back edge of side members 10 and 12 to complete the assembly. When assembled, the device comprises shelf for the display of package goods, a shelf for one or more packages separate from the package or packages on the display shelves, and storage for additional packages between the walls 10 and 12 on shelf 43.

60 Disassembled, the device may be compactly packed in flat form, ready for setting up when required. More or fewer shelves can be supplied and the dimensions varied without departing from the spirit of the invention.

I claim:

1. A display device having a seat angularly positioned for the support of an article of merchandise and comprising a plurality of blanks of sheet material, one of said blanks 70 being divided into a series of sections, there being a section extending from a second to a third of said sections and traversing intermediate sections, said first named section being cut from the body of said intermediate 75 and said third section, and the intermediate sections and said first section being articulated to coform said seat.

2. A display device having a seat angularly disposed for the support of an article of merchandise and comprising a plurality of blanks of sheet material, one of said blanks 80 having areas forming sides and a part of the front of said device, the front forming sections being folded to provide steps suitable to support articles for display, a second of said blanks coforming the front of said device and being divided into a series of sections, one of said sections extending from a second section to a third section and being 90 cut from the body of said third section and sections intermediate said second and third sections, said sections being turned angularly to one another at their adjacent edges to carry the second and third sections closer 95 together concurrently to said first section being articulated to form said seat.

3. A display device having a seat for the angular support of an article of merchandise and comprising a plurality of blanks having 100 areas forming sides and a part of the front of said device, a second of said blanks co-forming the front of said device and being divided into a series of sections, one of said sections extending from a second section to a third section and being cut from the body 105 of said third section and sections intermediate said second and third sections, said sections being turned angularly to one another at their adjoined edges to carry the second and third sections closer together concurrently to said first section being articulated to form said seat, and a third of said blanks providing a shelf for the storage of 110 additional articles of merchandise and being disposed beneath said seat and intermediate the sides of said device.

HARRY V. MARSH.
